UNITED STATES PATENT OFFICE.

DAVID E. DE VELBISS, OF SAN FRANCISCO, CALIFORNIA, ASSIGNOR TO PACIFIC COAST MANUFACTURING COMPANY, OF RENO, NEVADA, A CORPORATION OF NEVADA.

PRESSURE EQUALIZER FOR OIL BURNERS.

Application filed March 31, 1926. Serial No. 98,782.

My invention relates to means for equalizing the pressures of plural fluid streams to be united in a serviceable mixture, the object being to supply said fluids in predetermined volume ratio.

My invention, though applicable to any device or apparatus in which a plurality of fluids under independent, relatively variable pressures are led to a mixing chamber, is especially intended for use in connection with an oil-burner, in which steam under boiler pressure, and oil under pump pressure are supplied to the burner.

As the steam and oil should be supplied in predetermined volume ratio, and as the volume of the steam flowing to the burner varies markedly with the boiler pressure, and as, finally, the oil volume is approximately constant due to the pumping pressure (the slight pump-pulsation variation being for the moment disregarded), it is apparent that as the boiler pressure varies, the volume ratio of the two fluids will vary considerably.

By my invention, without mechanical connection between the independent pressure-regulating devices of the two fluids, the regulated steam pressure is made to directly, automatically and correspondingly vary the oil pressure; and by so equalizing the pressures, the predetermined volume ratio is preserved.

In the accompanying drawing in which the figure is a vertical section of my pressure equalizer, I show the preferred form of the device, it being understood that changes in form, arrangement and structure may be made without departing from the spirit of the invention as defined in the claims hereunto appended.

The device as here illustrated comprises a shell consisting of three flanged sections which from the top downwardly are designated by the numerals 1, 2 and 3, said sections being assembled by the bolts 4.

In the middle section 2 is the inlet 5 for the steam connection from the boiler, and the outlet 6 for the steam connection to the burner.

In the lower section 3 is the inlet 7 for the oil connection from the pump, and the outlet 8 for the oil connection to the burner.

Between the steam inlet 5 and outlet 6 is a valve seat 9 with which is associated a valve 10 of the balanced type. The stem 11

of this valve has its upper end fitted in a head piece 12 carried by a diaphragm 13 secured between the bolted flanges of the upper and middle shell sections 1 and 2.

A diaphragm-controlling spring 14 is housed within the upper shell section 1 and bears upon the head piece 12, said spring being adapted for tension adjustment by means of the head screw 15. The lower end of the valve stem 11 has fitted to it a small spring 16 to insure the closing of the valve in the absence of pressure.

Between the oil inlet 7 and outlet 8 is a valve seat 17 in which is a valve 18 of the balanced type. The stem 19 of valve 18 is fitted in a head piece 20 carried by a diaphragm 21 secured between the bolted flanges of the middle and lower shell sections 2 and 3.

A small spring 22 at the lower end of the valve stem insures the closing of the valve upon release of pressure.

In the middle shell section 2 is a by-pass 23 leading from the outlet side of the steam valve 10 and opening out into the space above the diaphragm 21.

The operation of the device will now readily be understood. Whatever steam pressure may be at the outlet side 6 of the diaphragm-controlled steam-valve 10, is, by the by-pass 23, imposed in equal degree upon the diaphragm 21, and said diaphragm, through the oil valve 18 establishes a like degree of oil pressure on the outlet side 8 of the oil valve 18. Thus at the outlets of both steam and oil, the respective pressures are equalized, and this is effected automatically by the control of one by the other.

Pressures being equalized, the desired volume ratio follows. As the boiler pressure changes and the resultant pressure control of the steam on the outlet side of the steam valve varies, the pressure of the oil on the outlet side of the oil valve varies and is kept equal to the controlled steam pressure so that whatever may be the variation in the regulated steam pressure the volume proportions of the two fluids will be kept constant.

It may further be noted that this automatic equalizing of the pressures of the two fluids through the instrumentality of the direct imposition of the outlet pressure of the steam, serves also to practically elimi-

uate on the outlet side of the oil valve, the slight pressure variation due to the pulsation of the pump.

I claim:—

- 5 1. A pressure equalizer for plural fluid streams under independent pressures, comprising a shell consisting of three flanged sections in successive unitary assemblage, the middle section having an inlet and an outlet for one of said fluid streams, and one of the end sections having an inlet and an outlet for the other of said fluid streams; a valve in the middle section controlling the passage of the first named stream from its inlet to its outlet; a separate valve in the end section for controlling the passage of the second named stream from its inlet to its outlet; a spring controlled pressure diaphragm seated in and traversing the union between the middle section and the other end section, said diaphragm being connected with and controlling the valve in said middle section; a second pressure diaphragm seated in and traversing the union between the middle section and the first named end section, said diaphragm being connected with and controlling the valve in said first named section; a by-pass formed within the middle section, adapted to impose the fluid pressure of the outlet side of the first named fluid stream upon the diaphragm connected with the valve controlling the second fluid stream; and a spring seated in said middle section and said first named end section, respectively, for returning said valves upon release of pressure.
- 10 15 20 25 30

2. A pressure equalizer for plural fluid

streams under independent pressure, comprising a shell consisting of three flanged sections in successive unitary assemblage, the middle section having an inlet and an outlet for one of said fluid streams, and one of the end sections having an inlet and an outlet for the other of said fluid streams; a valve in the middle section controlling the passage of the first named stream from its inlet to its outlet; a separate valve in the end section for controlling the passage of the second named stream from its inlet to its outlet; a spring controlled pressure diaphragm seated in and traversing the union between the middle section and the other end section, said diaphragm being connected with and controlling the valve in said middle section; a second pressure diaphragm seated in and traversing the union between the middle section and the first named end section, said diaphragm being connected with and controlling the valve in said first named section; a by-pass formed within the middle section, adapted to impose the fluid pressure of the outlet side of the first named fluid stream upon the diaphragm connected with the valve controlling the second fluid stream; and a spring seated in said middle section and said first named end section, respectively, for returning said valves upon release of pressure.

In testimony whereof I have signed my name to this specification.

DAVID E. DE VELBISS.
